Primary Examiner — Kevin Rudzinski(74) *Attorney, Agent, or Firm* — Kenneth M. Bush; Bush Intellectual Property Law**CLAIM**

I claim the ornamental design for a lighted headpiece for portable work light, as shown and described.

DESCRIPTION

FIG. 1 is a top rear perspective view of a lighted headpiece for portable work light showing my new design;

FIG. 2 is a bottom rear perspective view thereof;

FIG. 3 is a bottom front perspective view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a front elevational view thereof;

FIG. 9 is a rear elevational view thereof; and,

FIG. 10 is a top rear perspective view of the lighted headpiece for portable work light shown attached via a flexible cord to a table clamp.

The broken lines illustrating portions of the lighted headpiece for portable work light, flexible cord and table clamp form no part of the claimed design.

The ornamental design for a lighted headpiece for a portable work light wherein the headpiece includes a U-shaped portion having a plurality of light emitting diodes.
